UNITED STATES PATENT OFFICE.

CHARLES THOMAS MAGILL, OF SAN FRANCISCO, CALIFORNIA, ASSIGNOR TO BETHLEHEM SHIPBUILDING CORPORATION, LTD., OF BETHLEHEM, PENNSYLVANIA, A CORPORATION OF DELAWARE.

FURNACE FOR ANNEALING CONDENSER-TUBES.

1,307,744.

Specification of Letters Patent. Patented June 24, 1919.

Application filed January 8, 1919. Serial No. 270,120.

To all whom it may concern:

Be it known that I, CHARLES THOMAS MAGILL, a citizen of the United States, residing at San Francisco, county of San Francisco, 5 State of California, have invented a new and useful Furnace for Annealing Condenser-Tubes, of which the following is a specification.

In the annealing of condenser tubes as ordinarily carried out in practice it is customary for a workman to place one end of a tube into an annealing furnace, and after such end is annealed to reverse the tube and place the opposite end into the furnace until 15 the annealing operation is completed. This requires manual manipulation of the condenser tubes and increases materially the cost of the annealing operation.

In accordance with my present invention 20 the condenser tubes to be annealed are fed to the furnace in any desired manner, preferably automatically, and pass continuously through the furnace so that when they are discharged therefrom the requisite annealing operation has been completed.

By such construction and arrangement of an annealing furnace, thirty or more tubes 25 may be annealed per minute with a consequent decrease in the cost of the annealing operation.

With the above in view, my invention consists of a novel construction and arrangement of a furnace for annealing condenser tubes wherein provision is made to effect the 30 continuous travel of the tubes through the annealing furnace to simultaneously anneal both ends of the tubes. I also preferably provide means whereby the tubes will be turned or partially rotated during their 35 travel through the furnace.

It further consists of a novel construction and arrangement of an annealing furnace wherein two annealing furnaces are employed which are mounted on wheels so that 40 they can be readily adjusted for different lengths of pipe, and provision is made for conducting the fuel to each furnace.

It further consists of a novel construction and arrangement of a tube conveyer.

50 Other novel features of construction and advantage will hereinafter more clearly appear in the detailed description of my invention.

For the purpose of illustrating my inven-

tion, I have shown in the accompanying 55 drawing a typical embodiment of it which in practice will give satisfactory and reliable results. It is, however, to be understood that this embodiment is typical only and that the various instrumentalities of which 60 my invention consists can be variously arranged and organized, and that my invention is not limited to the precise arrangement and organization of these instrumentalities as herein set forth.

65 Figure 1 represents a top plan view of a furnace for annealing condenser tubes, embodying my invention.

Fig. 2 represents a furnace in side elevation, certain of the fuel pipes being in section.

70 Fig. 3 represents a front elevation of the furnace.

Fig. 4 represents, on an enlarged scale, a side elevation of one unit of the furnace and 75 certain of its adjuncts.

Similar numerals of reference indicate corresponding parts.

Referring to the drawings.

In accordance with my present invention, 80 I employ two annealing furnace units, each of which is constructed in a similar manner so that a detailed description of one will suffice for both. Each unit consists of an annealing furnace 1 which is built up of plates 85 and angles and consists of a flanged bottom plate 2, side plates 3 and 4 and a top plate 5. A flanged plate 6 is also employed at one side of the furnace, and a plate 7 is employed which forms a platform on which the 90 ends of the tubes roll. 8 designates the end plates which are slotted or cut out as indicated at 9, in order to provide mouths for the ends of the tubes during their travel 95 through the furnace. Each oven is mounted on standards 10 which are preferably formed of angle iron and which are provided with wheels or rollers 11. The plates are secured together in any desired manner and are preferably braced internally by means of 100 angle irons secured to the different plates. The top of the furnace is reinforced by the angles 12.

13 designates the main fuel inlet pipe which communicates with a pipe 14 which 105 extends longitudinally of a furnace unit along its side and is provided with a desired number of upwardly extending branches 15

- spaced from each other. Each of these branches 15 communicates with a burner 16 which has a steel pin 17 across its discharge end. The burner passes through an opening 5 in the front plate 4 and discharges into the annealing chamber 18 above which an end of a condenser tube 19 is to be passed. The pipe 14 is provided with laterally extending branches 20 and 21, and such branches of 10 opposite furnace units are connected by a flexible metallic hose 22, see Fig. 1. Each furnace is provided at its ends with bearings 23 in which are journaled the shafts 24 on which are mounted sprocket wheels 25. 15 Passing around the sprocket wheels 25 are the sprocket chains 26 which are provided with the upwardly extending lugs or pins 27 which contact with the condenser tubes 19 in order to effect their travel through the 20 furnace.

The shafts 24 are mounted in the bearings 23 in such a manner that the furnace units may be adjusted relatively to each other as desired. The sprocket wheels are driven in 25 any desired manner so that the shafts 24 are simultaneously rotated. In order to illustrate conventionally one manner of effecting the feed of the sprocket or conveyer chains 26, I have shown one of the shafts 24 as 30 having secured thereto a pulley 25 around which passes a belt 26 which passes around a pulley 27* on the drive shaft of a motor 28, see Fig. 3.

In order to effect a partial or complete 35 revolution of the tubes during their travel through the furnace, I provide means for varying the height at different places of the upper stretch of the conveyer and this is preferably accomplished by positioning 40 rolls 29, see Fig. 2, beneath the platform forming plate 7 so that during a portion of the travel of the conveyer chains the ends of the condenser tubes are free to roll on said platform while at other times they are 45 raised above the platform and are carried by the conveyer chains above and out of contact with said platform.

The pipes 15 which communicate with the pipes 14 are provided with gate valves 50 30 so that any desired branch fuel pipe can be properly controlled in accordance with the requirements met with in practice.

The operation of my novel furnace for annealing condenser tubes will now be 55 readily apparent to those skilled in this art and is as follows:

The sprocket chains are driven in any desired or conventional manner, and as illustrated, one of the shafts 24 is driven by the 60 motor 28. The condenser tubes 19 are fed in any desired manner to the conveyer chains 26. Assuming now that the burners 16 are operative and the annealing chamber 18 is being heated thereby, the condenser tubes are fed progressively through

the annealing chamber so that a large number of tubes are being annealed at the same time. The rollers 29 are located in such position that at predetermined intervals the upper stretch of the conveyer chains at 70 predetermined points will be permitted to sag so that the ends of the condenser tubes 19 will rest on the platforms 7 and be permitted to revolve. By such construction the ends of the tubes are uniformly annealed 75 on all sides. As the condenser tubes pass from the annealing furnace they are automatically discharged from the conveyer formed by the sprocket chains as will be apparent.

The annealing furnace can be readily adjusted to receive tubes of different lengths since all that it is necessary to do is to vary the spacing between the furnace units by moving them toward or away from each other and it is unnecessary to disconnect the flexible metallic hose 22 or to vary the adjustment of the sprocket wheels.

By the employment of my present invention a large number of condenser tubes may 90 be properly annealed at a minimum cost, and my invention is especially applicable to shipyards, and boiler and condenser plants, where it is desired to anneal uniformly and expeditiously the ends of tubes, 95 rods or the like, which can be simultaneously effected by my invention.

It will be understood by those skilled in that art, that it is desirable in an annealing furnace of this character, that the ends 100 of the articles to be annealed should be subjected to a continuous and somewhat prolonged heat for the desired period of the annealing operation and that not only should the heat be positively directed upon 105 the part to be annealed, but it is further desirable that the heating medium employed should be pre-heated to a certain extent, prior to ignition, in order to promote combustion.

Therefore, in accordance with my present invention, I provide longitudinally extending annealing chambers into which discharge a plurality of burners disposed in spaced relationship along the length of such 115 chambers, and valve controlled branch pipes communicate with said burners, so that the amount of fuel led to the burners may be regulated in accordance with the requirements met with in practice.

It will be apparent from the foregoing, that by arranging the annealing furnaces with their annealing chambers having their mouths wherein the ends of the articles to be annealed are received, juxtaposed or oppositely located to each other, as will be understood from Fig. 2, and by arranging continuous longitudinally extending heating chambers below the platforms 7 which are provided with a plurality of burners 130

16 whose lateral discharge ends project toward the heating chambers in such a way that the said discharge ends are at all times subjected to the radiant heat below the 5 platforms 7, the incoming fuel is at all times pre-heated prior to its ignition and by locating the series of inlet pipes 15 and burner pipes 16, as described within the furnace as will be understood from Figs. 10 3 and 4, the outside of the furnace is not encumbered or obstructed with piping or holes for the inlet of the heating medium, as has been the practice with annealing furnaces with which I am familiar.

15 It will therefore be seen in my invention, owing to the construction of the overhanging portions of the furnace and the positioning of the platforms 7 with respect to the burner pipes, that a maximum degree 20 of heat can be continuously applied to the ends of the articles to be annealed, while the latter travel through the furnace, so that when said articles have completed their travel through the furnace, they will upon 25 their exit therefrom be expeditiously and effectively annealed to the desired extent.

I am aware that it has been heretofore proposed to heat the ends of metal spokes by the application of a heating medium 30 thereto at two opposite holes in the sides of the heating furnace wherein said heating medium is injected from the outside of the furnace. Such construction, however, is not capable of attaining results I have obtained 35 by pre-heating the heating medium prior to its discharge into the furnace and by employing a plurality of burners arranged in succession below the platform upon which the articles to be annealed are adapted at 40 intervals to contact with for the purpose described.

It will now be apparent that I have devised a novel and useful construction of a furnace for annealing condenser tubes which 45 embodies the features of advantage enumerated as desirable in the statement of the invention and the above description, and while I have, in the present instance, shown and described a preferred embodiment thereof 50 which will give in practice satisfactory and reliable results, it is to be understood that such embodiment thereof is susceptible of modification in various particulars without departing from the spirit or scope of the 55 invention or sacrificing any of its advantages.

Having thus described my invention, what I claim as new and desire to secure by Letters Patent, is:—

60 1. An annealing furnace, comprising furnace units, each unit having a longitudinally extending annealing chamber, and an open side to receive an end of a tube, means to heat said chambers, a tube conveyer, and 65 means coöperating with said tubes during

their travel through the furnace to revolve them at predetermined intervals and thereby insure the uniform and simultaneous annealing of both ends of the tubes.

3. An annealing furnace, comprising furnace units relatively adjustable with respect to each other, each unit having an annealing chamber, a platform along said chamber and an open side to permit an end of a tube to extend into an annealing chamber, means to 70 heat said chambers, sprocket chains along the open side of said units and having lugs to engage the tubes, means to drive said sprocket chains, and means coöperating with the upper stretch of said sprocket chains to 75 cause the tubes to be at times out of engagement with said platform and at other times to contact with said platform to effect the turning of said tubes during their travel through said annealing chamber. 80

3. An annealing furnace, comprising furnace units spaced apart, each unit having a longitudinally disposed annealing chamber and an open side, a fuel pipe extending along each unit, branch pipes extending from said fuel pipe, burners for said annealing chambers and in communication with said branch pipes, flexible hose in communication with the ends of said first pipes, 90 brackets carried by said units, shafts journaled in said brackets, sprocket wheels fixed to said shafts, and sprocket chains passing around said sprocket wheel and having means to engage a tube to effect its feed 95 through the annealing furnace. 100

4. An annealing furnace of fabricated construction, comprising furnace units spaced apart, each unit having top, bottom, side and end plates connected together, standards of angle formation supporting 105 each unit, wheels on said standards, each unit having an annealing chamber extending longitudinally through it and an open side to receive an end of a tube, a plurality of burners spaced along the inside of the furnace to heat said annealing chamber, means to feed fuel to said burner, and means to move a number of tubes through said furnace to effect the simultaneous annealing of both ends of the tubes. 110

5. An annealing furnace of fabricated construction, comprising furnace units spaced apart, each unit consisting of top, bottom, side and end plates connected together and suitably supported, said end plates having an opening through which the ends of the tubes pass, each unit having an annealing chamber extending longitudinally thereof, and means to feed tubes to cause their ends to pass through the annealing chambers of said furnaces and effect the simultaneous annealing of both ends of the tubes. 115

6. In an annealing furnace, means for simultaneously annealing the outer ends of a tube, rod or the like, and means for auto- 120 125 130

matically rotating said ends at intervals during the annealing operation.

7. In a device of the character stated, two annealing furnaces having overhanging tops, and open longitudinally extending mouths juxtaposed to each other for the reception of the ends of the articles to be annealed, platforms extending inwardly from the annealing chamber of each furnace, 10 means for propelling the ends of the articles to be annealed through said annealing chambers, and means for causing the ends of said articles to contact with said platforms at intervals, so as to be automatically rotated during the annealing operation.

8. In a device of the character stated, two annealing furnaces having overhanging tops, and annealing chambers having open inwardly extending longitudinal mouths, 20 juxtaposed to each other for the reception of the ends of the articles to be annealed, platforms, inwardly extending from said annealing chambers forming the bottom of

said mouths, passages below said mouths leading to said annealing chambers, and inlet pipes for the heating medium having upright members located within the furnaces and laterally extending branches extending inwardly below said platform and discharging into said annealing chambers, whereby 30 the heating medium is pre-heated prior to ignition therein.

9. In a device of the character stated, a furnace unit, having longitudinally extending annealing chambers provided with openings to receive an end of the article to be annealed, means to heat said chambers, a conveyor for the article to be annealed, and means coöperating with said article during its travel through the furnace to revolve it 40 during the annealing operation.

CHAS. THOMAS MAGILL.
